UNITED STATES PATENT OFFICE.

RICHARD W. OWEN, OF CHICAGO, ILLINOIS, ASSIGNOR TO THE LANZ,
OWEN & COMPANY, OF SAME PLACE.

DESIGN FOR A SABRETASH.

SPECIFICATION forming part of Design No. 33,807, dated December 25, 1900.

Application filed January 20, 1900. Serial No. 2,211. Term of patent 14 years.

To all whom it may concern:

Be it known that I, RICHARD W. OWEN, a citizen of the United States, residing at Chicago, county of Cook, and State of Illinois, 5 have invented and produced a new and original Design for a Sabretash, of which the following is a specification, reference being had to the accompanying drawings, forming a part thereof.

10 In the drawings, Figure 1 is a view in perspective of the sabretash. Fig. 2 is a transverse section in line with the lines 2 2 of Fig. 3, and Fig. 3 is a rear view of the sabretash.

The leading features of the design are as 15 follows:

In general contour the sabretash has the form of an oblong rectangular pouch having flat front and rear sides 10 and 11 and sides in bellows form connecting the front and rear 20 sides along three of their edges. The rear side 11 is prolonged beyond the open end of the pouch, as shown at 14, and the front side 10 is also prolonged beyond such open end, as shown at 15; but this prolonged portion 25 is of less length than the prolonged portion 14. Inner partitions 16 and 17 are located between and parallel with the sides 10 and 11 and extend from edge to edge thereof, but are spaced apart therefrom intermediate of 30 their side edges. A pocket 18 is located upon the face of the side 10 and is of less area than such side and located in one of the upper corners thereof, this pocket having a plain front face which is cut away diagonally across

from its outer upper corner, and the vertical 35 sides of such pocket are each provided with a bellows fold. A smaller pocket 19 is located upon the face of the front side 10 and at the side of the pocket 18, and above this smaller pocket there are a series of loops 20, 40 21, 22, and 23. A flap 24 extends outwardly from one of the vertical edges of the front side 10 and is bent a short distance from its juncture with such side, so as to be inclined across the pocket 19 and loops 20 to 23. The 45 outer upper corner of the flap is cut away diagonally. A pair of loops 25 26 are located upon the rearward side 11, and a pair of rings 27 28 project upwardly from such loops, and to each of such rings is secured a hook 31. 50 A socketed lock-case 29 is secured to the front side 10, below the pocket 18, and has a shield-shaped base and an approximately square body portion superimposed upon such base. A hook 30 projects from the upper 55 edge of the flap 14.

Having described my invention, what I claim as new, and desire to secure by Letters Patent, is—

The design for a sabretash, as herein shown 60 and described.

In testimony whereof I have signed my name to this specification in the presence of two subscribing witnesses.

RICHARD W. OWEN.
